MECHANICAL PENCIL

Isidor Chesler, West Orange, N. J., assignor to
 Eagle Pencil Company, New York, N. Y., a corporation of Delaware

Application October 18, 1930, Serial No. 489,546

9 Claims. (Cl. 120—18)

This invention relates to mechanical pencils and to methods of making the same.

Mechanical pencils are manufactured in great quantities to sell at moderate and low prices and makers have been continuously faced with the problem of providing the demand for relatively cheap pencils capable of giving good service without getting out of order. A common form of mechanical pencil is provided with a lead propelling rod, a guide tube therefor, a screw for advancing the lead rod, and a barrel which encloses the foregoing and other parts which are essential and peculiar to any particular design of mechanical pencil. In many types of pencils the barrel of a pencil performs the function of a grip and is provided with a tip at its lower end and other appendages which hold the working parts in assembled relation. The barrels of many of these pencils are at the present time made from wood or of metallic tubing and some of the pencils are provided with screw tubes by which the lead propelling rods are advanced. In the interest of low manufacturing costs it has been the practice to provide crude fits of the tip, through which the lead travels at the lower end of the pencil, with the guiding tube and barrel. Also, the screw tube has been poorly constructed and fitted. Because of these conditions and the lack of the exercise of the care necessary for the correct assembling of parts, the propelling and retracting actions are often accompanied by an appreciable amount of friction. The result is that wear and incident abuse because of hard operation frequently limit the life of a pencil possessing such structural characteristics.

It is, therefore, the object of my invention to overcome defects of the kind referred to and to enable the production of an inexpensive mechanical pencil which has moving parts possessing smoothness in operation. To this end I have eliminated the separable barrel and screw and have made these members as one member. A perfect screw of rigid construction is obtained. Also, undesired seams and loose fits are obviated, and by such a construction the tip through which the lead passes at the end of the pencil may be integrally associated with the barrel.

Another object of my invention is to provide a mechanical pencil having a moulded grip or barrel, and methods by which such a pencil may be flawlessly made in large quantities on an economic production basis. The barrel is moulded or cast from plastic material with the hollow tip through which the lead passes affixed thereto as an integral part. In one of the methods by

which a moulded barrel having an internal screw is formed I have developed a novel method of casting within a portion of a cavity, which method has uses other than for the manufacture of pencils.

With these and incidental objects in view the invention involves certain novel features of construction and combination of parts, the essential elements of which are set forth in the appended claims and a preferred form of embodiment of which is described hereinafter with reference to the drawings which accompany and form a part of the specification.

In the drawings:

Fig. 1 is a longitudinal section of a mechanical pencil embodying the present invention.

Fig. 2 is a longitudinal section through the lower end of the pencil with the core used in its manufacture in place.

Fig. 3 is a section on line 3—3 of Fig. 2.

75

Fig. 4 is a cross-section on line 4—4 of Fig. 3.

Figs. 5, 6, 7 and 8 are cross-sections on line 5—5, 6—6, 7—7, and 8—8 respectively of Fig. 1.

Fig. 9 is a longitudinal view, partly in section, of the guide tube, lead carrying tube and lead propelling rod.

Fig. 10 is another longitudinal view of the members illustrated in Fig. 9.

Fig. 11 is a cross-section on line 11—11 of Fig. 10.

85

Fig. 12 illustrates how the barrel may be moulded.

Fig. 13 illustrates the barrel and tip of the pencil shown in Fig. 12 with the core removed.

Fig. 14 is a longitudinal section of the tip of Figs. 12 and 13 before it is mounted on the core.

Figs. 15, 16, 17, 18 and 19 are illustrative of the various elements used in the method of moulding the barrel of the pencil illustrated in Figs. 1, 2, 3 and 4.

Fig. 20 illustrates the relation of a core in the barrel of a pencil designed for a mechanical movement different from that of the pencil of Fig. 1.

Fig. 21 is a portion of the barrel of the pencil of Fig. 20 with its lead controlling parts in place.

Fig. 22 is a section on line 22—22 of Fig. 21.

Figs. 23 and 24 are different views of the lead controlling parts for the pencil illustrated in Figs. 21 and 22.

105

Mechanical pencils known as the "propel-repel-expel" type are usually provided with a guide tube having a longitudinal slot through which projections may extend for engaging a helical groove. One of these projections is affixed to a

110

lead carrying tube which is adapted to engage the lead. This tube is propelled along the axis of the guide tube as the result of a rotary motion between the guide tube and the barrel or sleeve of 5 the pencil as the projection travels in the helical groove. A rod with a similar projection is provided for expelling the lead from the tube. The functioning members of some other types of mechanical pencils omit the lead expelling rod or 10 the lead carrying tube but the member which controls the position of the lead within the pencil is carried in either direction along the axis of the pencil, depending upon the direction of rotation of the guide tube relative to the barrel. 15 As will subsequently appear, certain features of my invention embody improvements for any mechanical pencils of types similar to those al-luded to hereinabove.

While certain features of my invention are 20 useful in different types of mechanical pencils, I have chosen to illustrate my invention embodied in what is known as a "propel-repel-expel" type of pencil. In this latter type of pencil the lead expelling rod is mounted for sliding movement within the lead carrying tube and the projection carried by the lead expelling rod extends through a slot in the lead carrying tube and the longitudinal slot in the guide tube and into a helical groove. These members are illustrated 25 in all three of the pencils shown in the drawings. In the ordinary use of the pencil, the projection from the lead carrying tube and the projection from the lead expelling rod are spaced from each other a distance equivalent to two convolutions 30 of the helical groove, and in this relation the lead carrying tube is open for the reception of a lead. This relation is maintained so long as there is sufficient lead to be useful for writing purposes. When the lead carrying tube and lead expelling 35 rod have traveled to the tip end of the pencil as the lead has been used, further travel of the projection on the lead carrying tube is terminated.

In the pencils illustrated in Figs. 1, 9 and 10 the projection on the lead carrying tube enters a recess at the end of the helical groove and this recess permits the projection to rotate freely, and prevents further advancement of the projection and lead carrying tube. When the projection from the lead carrying tube has reached the bottom 40 of this recess and the rotation of the guide tube is continued, the projection from the lead expelling rod will continue to travel along the helical groove and move the lead expelling rod relative to the lead carrying tube, with the result that the lead is expelled from the lead carrying tube. This condition of the pencil is illustrated 45 in Fig. 1. After a lead has been expelled and it is desired to insert new lead, the movement of the guide tube in the barrel of the pencil is reversed and the projection from the lead expelling rod is caused to travel in the groove in the pencil in a direction away from the tip. When the lead expelling rod has been moved sufficiently, a lead may be inserted in the end of the lead 50 carrying tube. The lead expelling rod moves relatively to the lead carrying tube during one revolution of the guide tube and, thereafter, further rotary movement would cause the lead expelling rod to carry the lead carrying tube with 55 it and cause the projection from the lead carrying tube to engage the helical groove of the pencil. In this relation the two projections are spaced from each other two convolutions of the helical 60 groove and the lead may be carried back into the pencil.

The pencil of the type illustrated in Figs. 1, 9 and 10 has members associated together and capable of coacting in the manner above outlined. In this pencil the guide tube 10 has a longitudinal slot 11 along which the projections of the lead carrying tube and lead expelling rod travel as the guide tube is rotated relative to the sleeve or barrel 12. The lead carrying tube 13 has a longitudinal slot 14 through which extends the projection 15 which is mounted upon the lead expelling rod 16. This projection 15 is in the form of a looped member having smooth rounded edges adapted for easy movement within the helical groove 17 of the pencil. This loop 15 may be a part of the lead expelling rod 16 or may be merely a looped element secured thereto. The slot 14 is of such a length as to permit the projection 15 to move the pitch of the helical groove without causing movement of the lead carrying tube.

As may be seen in Figs. 1, 6, 9, 10 and 11, the lead carrying tube 13 has a projection which is formed by a pair of ears extending from the material of the tube beyond the tubular dimension of the guide tube 10. These ears 18, 19 are 100 shouldered to support a washer 20 and extend through and are bent over the washer. The washer preferably is round and of such a diameter as to easily engage the helical groove 17. The design of this projection and the function 105 which it serves is a feature of the present invention. It is admirably suited to afford smooth action in the operation of the pencil as it travels along the helical groove. Frequent cause of failures of mechanical pencils of the "propel-repel-expel" type are directly assignable to weakness in the forms of projections used and to the lack of appreciation of the sliding fit conditions existing when the projection passes from the helical groove to the recess 21 near the lower 110 end of the pencil. The form of the projection illustrated gives sufficient strength to withstand the stresses likely to be placed upon the projection and its width and form render it well suited for smooth entry into the helical groove from 115 the clearance recess and for guidance by the thread.

As illustrated in Fig. 1 the lead carrying tube and lead expelling rod have been moved to their extreme positions at the lower end of the pencil. In this position the projections are in their closest relation; that is, their spaced distance is the pitch of the helical groove 17. From this position the lead expelling rod may be drawn into the lead carrying tube by the rotation of 125 the guide tube while the projection from the lead carrying tube rotates freely within recess 21. When projection 15 has moved the distance of 130 the pitch of the helical groove further rotation will cause a pull upon the lead expelling rod because of the contact had between projection 15 and the inner end of slot 14, with the result that the projection from the lead carrying tube will engage the entrance to the helical groove 17. This movement has occasioned friction and has been the cause of failures but my pencil is capable of smooth and uninterrupted motion.

In addition to the smoothness of operation contributed because of the form of the projection, the connecting together of the tip 23 with the barrel 12 as an integral member without intermediate seams or laps is a contributing factor. This enables the making of the helical groove continuous with the recess.

In prior practices the tip of the pencil through

- which the lead passes was made up in some cases, of more than one member and the tip was connected to a wooden barrel. The member bearing the helical groove was independent of the wooden barrel and usually within a sleeve or in the form of a spiral tube. The recess in which the projection from the lead carrying tube entered from the helical groove often consisted of merely an interruption of the helical groove. 5
- The poorly constructed joints which frequently exist in such pencils are eliminated in my pencil in which the helical groove is integrally associated with the barrel and the tip is joined to the barrel as one member. This construction has 10 been made possible by the development of methods, which will later be described, which make it possible to mould the barrel from a composition such as, for example, a phenolic condensate product. 15
- In the moulding operation the tip is joined together with the barrel as one member and the larger bore within the tip is a continuation of the helical groove in the barrel of one type of pencil or of the bore in the barrel in another 20 type of pencil. In addition to eliminating the use of more than one member to serve for a groove and as a grip by which the pencil may be manipulated, I have provided a new method which enables the tip to be made of one piece. 25
- This feature in itself is an economical saving in the cost of manufacturing mechanical pencils. 30
- Having reference to Figs. 1, 2, 3 and 4 which relate to one method of making the pencil, the tip 23 is turned from a single member, preferably a metallic member. This member is drilled for the purpose of forming the recess 21 which receives the projection carried by the lead carrying tube, Fig. 1. It may also be drilled at 25 for receiving the lower end of the guide tube 10. Although it is 35 not necessary that the guide tube extend into the tip, it is an advantage of construction to provide a bearing at 25 for supporting the lower end of the guide tube. A bore 26 of less diameter is provided for receiving the lead carrying tube when 40 the tube is moved to the lower end of the pencil as illustrated in Fig. 1. Of course, the tip is provided with the usual hole 27, through which the lead passes. The tip 23 is shouldered at 28 in order that it may be firmly held by and embedded 45 within the moulded composition of the barrel 12. The tip which has just been described is illustrated in detail in Figs. 1, 2, 3, 4, 5 and 6, and the method by which the barrel of the pencil is moulded to this tip is illustrated in steps in Figs. 15 to 19 50 inclusive.
- As illustrated in Fig. 1, the upper end of the pencil has a rubber supporting ferrule 29 which engages by friction a cap 30 which is secured to the end of the guide tube 10 by means of a pin 60 31. By rotating the ferrule 29 the lead carrying tube may be made to travel along the guide tube in either direction depending upon the direction of rotation of the guide tube relative to the barrel.
- The mould in which the barrel of the pencil 65 may be formed and connected with the tip is illustrated in Fig. 18. Before moulding the barrel, the tip 23 is engaged by means of a core 33 which is a screw for forming the internal groove of the barrel, Fig. 16. Preferably the core 33 is tapered 70 slightly at the end which engages the bore 21 in order that a tight fit of the core with the bore may be assured. Figs. 2 and 3 have been laid out on an enlarged scale in order to make clear the relation of the core with the bore. After 75 the tip and the core have been engaged in this
- manner a piece of malleable metal 35, such as soft aluminum, Fig. 17, is driven through a hole 36 in the skirt 37 of the tip 23 in such a location as to enter and fill the groove between successive turns on the core 33. As assembled, the tip 23 and the core 33 are placed within a mould, Fig. 18, with the tapered end of the tip 23 in close contact with one end of the mould in such a manner as to close that end. The plastic material which is to form the barrel of the pencil is then forced into the mould and caused to take the form of the mould, as the result of sufficient pressure to insure that a perfect cast of the barrel is obtained. The piece of malleable metal 35 will operate to prevent the entrance of the plastic material along the groove of core 33 beyond itself and thereby prevent the entrance of the plastic material to the recess 21. In the finished product, after the composition has set, the piece 80 35 will be the end of the internal thread of the barrel, a portion of which extends within the bore 34, Fig. 4. This construction insures a continuity of the helical groove 17 to a definite point within the recess 21 with moulded composition 85 extending within the metallic tip member as far 90 as the piece 35.
- When the moulded composition has set, the mould may be removed and the core removed from within the barrel. The barrel is then ready 95 for receiving the movable parts of the mechanism which have been described hereinabove. 105
- The foregoing method of producing the barrel of moulded composition involves the solution of the problem of moulding or casting within a cavity. A tight fit at the periphery of the thread 110 of the core 43 with the bore or recess 21 insures that plastic composition may enter the bore only along the groove of the core, and the distance of entry of the plastic material along the groove is determined by the position of a pin. In this manner 115 the flow of plastic material within the cavity or recess 21 is prevented even though some of the material forms the thread within the bore of the recess.
- Another method by which the barrel may be 120 moulded is illustrated in Figs. 12 and 13. This method requires the use of a metallic tip 40 which has a portion of a thread 41 tapped therein. This thread extends to the recess 42, Fig. 14. In this latter method of moulding, the core 43, Fig. 12, 125 is screwed into the end of the tip. The core and tip are placed in this condition within a mould similar to that used in the method of moulding above described. After the moulded composition 130 filled the mould and has set about the tip and core, the assembled members may be removed from the mould and the core 43 withdrawn. As illustrated in Fig. 13 this method results in the production of a barrel and tip integrally associated with an internal helical groove 44 of the 135 composition of material continuing within the metallic tip.
- While there are various types of mechanical pencils employing different forms of movable parts for controlling the position of a lead which 140 may be improved by the use of my invention, I have chosen to illustrate the application of my invention to a pencil of the "propel-repel-expel" type, since this type of pencil embodies mechanical features in addition to those which are characteristic of other types of pencils. In the foregoing description I have disclosed a special kind of "propel-repel-expel" pencil in that each of the two modifications, the one illustrated in Fig. 1 and the one illustrated in Fig. 13, has a recess for 145 150

permitting the projection from the lead carrying tube to rotate when it has reached the lower end of its path of travel.

In Figs. 20 to 24, inclusive, I have illustrated another kind of "propel-repel-expel" type of pencil which does not embody the use of a recess for receiving the projection from the lead carrying tube. The tip 45 for this pencil is, therefore, of a different character. This tip is turned and drilled in a manner similar to the tips previously described but in view of the fact that less machining is necessary its cost to manufacture is much less. This tip likewise may be made from a single piece of material such as brass, German silver, or other material having sufficient strength. It is tapered on its outside surface at its lower end and has drilled therein a hole 46 for permitting the passage of a lead. The hole 47 is adapted to receive the lead carrying tube 48 when that tube has descended to the tip end of the pencil, Fig. 21. It is convenient to turn the upper end of the tip 49 in the form of a hollow cylinder. For moulding the barrel 50 of the pencil the tip is engaged by a core 51 in the manner illustrated in Fig. 20 and the tip and core are placed in a mould similar to that illustrated in Fig. 18. The process of moulding is thereafter similar to that described hereinabove. In order to obtain a tight fit between the tip 30 and the core the pilot 52 of the core is tapered slightly. While the bore of the cylinder 49 could be tapered in lieu of tapering the pilot, it is preferable to taper the pilot since such procedure is less expensive. Even though high pressures 35 are utilized in moulding the phenolic condensate or other composition the fit between the tip and the core is such as to prevent any extrusion of the moulded composition into the bore of the tip.

40 The shoulder 53 may be turned and it serves for interlocking the tip with the barrel of the pencil.

When the barrel has been moulded and has set the core 51 is removed and the barrel is ready 45 to receive the moving parts which control the position of the lead. Referring to Figs. 21, 22, 23 and 24, these parts comprise the lead carrying tube 48 which is mounted for sliding movement along the axis of the slotted guide tube 55 as the guide tube is rotated thereby causing the projection 56 to travel along the helical groove 57 and actuate the lead carrying tube. In the mechanism illustrated, the lead expelling rod 58 in separable from the lead carrying tube 48 but it 55 also is actuated along the axis of the pencil as its projection 59 is caused to travel in the helical groove 57. The lower end 60 of the guide tube 55 is journaled in the hollow cylinder 49. At 60 the lower end of the helical groove the slotted guide tube 55 is slotted laterally at 61 for permitting the guide tube to turn relatively to the lead carrying tube and projection 56 when the projection has traveled to its lowest limit in the helical groove.

Since it is apparent from the foregoing that the advantages incident to moulding the barrel of a mechanical pencil with an internal helical groove may be availed of for improving many different 70 types of pencils, it is unnecessary to refer to additional applications of the invention in other mechanical pencils. I desire it to be understood that it is not intended to confine the invention to the specific forms of improvements herein disclosed for it is susceptible of embodiment in

various forms, all coming within the scope of the claims which follow.

I claim:

1. In a mechanical pencil, the combination comprising an internally threaded sleeve and a slotted guide tube mounted for rotation within said sleeve, a lead carrying tube slidable within said guide tube and having a projection, said projection comprising a pair of ears holding a washer having a diameter substantially equal to the width of the groove of the thread in said sleeve with which it is in engagement, and a lead propelling rod extending within said lead carrying tube, said lead propelling rod having a projection for engaging the thread of said threaded sleeve. 80

2. In a mechanical pencil, the combination comprising an internally threaded sleeve and a slotted guide tube mounted for rotation within said sleeve, a lead carrying tube slidable within said lead carrying tube, said lead propelling rod and said lead carrying tube each having a projection engaging the thread of said threaded sleeve, at least one of said projections including a circular disc working in the groove of the thread and of a diameter nearly approximating the width of such groove. 95

3. In a mechanical pencil, the combination comprising a barrel whereby the pencil may be gripped, said barrel having an internal thread, a pencil tip held in locked relation by said barrel, said tip having a hole for the passage of lead and a recess threaded in continuation of the internal thread of said barrel, a guide tube within said barrel, and a lead carrying tube having a projection adapted to follow the thread of said barrel and threaded recess upon rotation of the lead carrying tube. 100

4. In a mechanical pencil, the combination comprising a barrel whereby the pencil may be gripped, said barrel being of a moulded composition and having an internal helical thread, a lead carrying tube having a projection engaging the helical thread, a slotted guide tube, a lead expelling rod within said lead carrying tube, said lead expelling rod having a projection engaging the helical thread, and a tip at one end of said barrel, said tip comprising a single body with a hole through its axis having different diameters, 110 the different diameters being provided for receiving the lead, lead carrying tube, guide tube and the projection of said lead expelling rod respectively. 120

5. In a mechanical pencil, the combination comprising a barrel whereby the pencil may be gripped, said barrel being of a moulded composition and having a bore threaded internally, a lead carrying tube having a projection engaging the helical thread, a slotted guide tube, a lead expelling rod within said lead carrying tube, said lead expelling rod having a projection engaging the helical thread, and a metallic tip fixedly associated with said barrel, the moulded composition of said barrel being in engagement with a portion of the exterior of said tip, said tip having a clearance recess disposed beyond the end of the threaded bore of the barrel for enabling the travel of the projection of the lead carrying tube 130 into the tip and being suitably holed for receiving the lead and lead carrying tube. 140

6. In a mechanical pencil, the combination comprising a barrel whereby the pencil may be gripped, said barrel being of a moulded composi- 150

- tion and having a bore threaded internally, a lead carrying tube having a projection engaging the helical thread, a slotted guide tube, a lead expelling rod within said lead carrying tube, said recess being adapted to receive the projection on said lead carrying tube to enable rotation thereof during movement of the lead expelling rod in relation to the lead carrying tube.
- 5 8. In a mechanical pencil the combination with a barrel of plastic composition having an integral internal helical thread, of a metallic tip having a passage for the lead of the pencil, said barrel including an integral portion interlocking with the tip to block disassembly of the tip and barrel and retain the tip in proper position with respect to the barrel and a lead carrying member including a portion working in the groove of the thread. 80
- 10 7. In a mechanical pencil, the combination comprising a sleeve having an internally threaded bore and a guide tube mounted for rotation within said sleeve, a lead carrying tube, a lead propelling rod within said lead carrying tube, said lead carrying tube and said lead propelling rod each having a projection engaging the thread of said sleeve, said projections being spaced from each other a distance necessary to expel a lead from the lead carrying tube by movement of the lead propelling rod relative to the lead carrying tube, a metal tip having a hole for laterally supporting a lead disposed in said lead carrying tube, said tip being fixedly attached to said sleeve and having a clearance recess beyond the helical groove of the threaded bore of said sleeve, said recess being adapted to receive the projection on said lead carrying tube to enable rotation thereof during movement of the lead expelling rod in relation to the lead carrying tube. 85
- 15 9. In a mechanical pencil the combination with a barrel of plastic composition having an integral internal helical thread of a metallic tip having a passage for the lead of the pencil, said barrel including an integral portion interlocking with the tip to block disassembly of the tip and barrel and retain the tip in proper position with respect to the barrel, said tip having an external annular groove therein receiving an integral internally circular inwardly extending portion of the plastic barrel. 90
